UNITED STATES PATENT OFFICE

170,497

COLLAPSIBLE VALET STAND

Ernest W. Ehrman, New York, N. Y.

Application December 5, 1952, Serial No. 22,576

Term of patent 3½ years

(Cl. D33—8)

To all whom it may concern:

Be it known that I, Ernest W. Ehrman, a citizen of the United States, residing in New York city, in the county of New York and State of New York, have invented a new, original, and ornamental Design for a Collapsible Valet Stand, of which the following is a specification, reference being had to the accompanying drawing, forming part thereof.

Fig. 1 is a perspective view of a collapsible valet stand in a standing position showing my new design;

Fig. 2 is a front elevational view thereof;

Fig. 3 is a side elevational view thereof;

Fig. 4 is a front elevational view thereof in a collapsed position;

Fig. 5 is a side elevational view thereof in a collapsed position.

I claim:

The ornamental design for a collapsible valet stand, as shown.

ERNEST W. EHRMAN.
